INFANT FEEDING BOTTLE

Arthur Hurst, Golant, near Fowey, Cornwall, England,
assignor to Adonsell Limited, Birmingham, England

Filed Apr. 3, 1975, Ser. No. 564,839

Claims priority, application Great Britain Nov. 19, 1974

Term of patent 14 years

Int. Cl. D9—01; D28—01

U.S. Cl. D83—8 A

FIG.1.

FIG.2.

FIG.3.

FIG.4.

FIG.5.

FIG. 1 is a top plan view of an infant feeding bottle showing my new design;

FIG. 2 is a bottom plan view thereof;

FIG. 3 is a front elevation thereof;

FIG. 4 is a side elevation thereof; and

FIG. 5 is a cross-section taken on line 5—5 of FIG. 3.

I claim:

The ornamental design for an infant feeding bottle, as shown and described.
